B. T. LEVEQUE,
INSOLE HEEL SEAT SMOOTHING MACHINE.
APPLICATION FILED AUG. 21, 1917.

1,303,926.

Patented May 20, 1919.

Boswell G. Lucy

UNITED STATES PATENT OFFICE.

BERNARD THOMAS LEVEQUE, OF WENHAM, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

INSOLE-HEEL-SEAT-SMOOTHING MACHINE.

1,303,926.

Specification of Letters Patent. Patented May 20, 1919.

Application filed August 21, 1917. Serial No. 187,489.

To all whom it may concern:

Be it known that I, BERNARD T. LEVEQUE, a citizen of the United States, residing at Wenham, in the county of Essex and State 5 of Massachusetts, have invented certain Improvements in Insole-Heel-Seat-Smoothing Machines, of which the following description, in connection with the accompanying drawings, is a specification, like reference 10 characters on the drawings indicating like parts in the several figures.

This invention relates to machines for smoothing the heel portion of the insole of a boot or shoe.

15 It is customary to attach a heel to a shoe by means of nails driven from the outside through the heel, the outsole and the insole, the ends of the nails being clenched inside the shoe on the heel portion of the insole 20 and being covered in the finished shoe by a heel pod, or sock lining. It frequently happens that the clenched ends of these heel attaching nails project slightly above the surface of the insole and thereby cause dis- 25 comfort to the wearer of the shoe. The object of the present invention is to provide a machine which will effectually smooth and to an extent shape the heel portion of the insole so as to produce a comfortable sup- 30 port for the heel of the wearer of the shoe.

One feature of the invention comprises a shaft, a cutting tool mounted upon the end thereof, a suction conduit the mouth of 35 which extends around said tool and serves as a gage to limit the depth of cut of said tool, and means for rotating said shaft. With this construction the heel seat of the insole may very quickly be smoothed and shaped, the suction of air through the conduit acting to remove whatever dust or chips are formed and leaving the inside of the shoe clean.

This and other features of the invention, including certain details of construction 45 and combinations of parts, will be described in connection with an illustrative machine and pointed out in the appended claims.

Referring now to the accompanying drawings,—

50 The figure is a side elevation of a machine in which the present invention is embodied, a shoe being shown in position to be operated upon.

Mounted on or fast to the head of the ma-

chine is a suction conduit comprising a main 55 portion 3 to the right-hand end of which any suitable suction apparatus may be connected, and an end portion 103, said last-named portion terminating in a mouth 5 which extends around a cutter 7. The cutter, herein shown as an end milling cutter having a slightly convex cutting face adapted to form a slight depression in the heel portion of the insole of a shoe, is fast to the lower end of an upright shaft 9 journaled in 60 a bearing 11 which is integral with the main portion 3 of the conduit. The main portion 3 and the end portion 103 are connected by a lap joint as shown to permit vertical adjustment of the end portion. A screw 13 which 65 passes through a slot 15 in the end portion and is threaded into a boss on the bearing 11 provides means for holding the end portion 103 in adjusted vertical position. A pulley 17 is fastened to the upper end of the shaft 9 70 by a pin 19; and a belt 25 runs around this pulley, over guide pulleys 27 and around a pulley 29 on the driving shaft 31.

In the operation of the machine, the conduit is adjusted until the tool 7 projects the 80 desired distance below the mouth 5. A shoe is then pressed up against the tool in the manner indicated in the figure whereupon the tool smooths and shapes the heel seat of the insole, the dust and chips generated during this operation being carried away 85 through the suction conduit. If after repeated operations the tool becomes clogged, a treadle 41 may be depressed to raise a clearing brush 33 into contact with the tool. 90 The brush is rotatably mounted on one end of an arm 35 which is pivoted to the frame of the machine at 37, the other end of the arm being pivotally connected to a treadle rod 39 which is connected at its lower end to 95 the treadle.

It should be particularly noted that the mouth of the suction conduit, by arresting the upward movement of the shoe, serves as a gage to determine the depth of cut of the 100 tool and that thereby a very compact and efficient construction results.

Although the invention has been set forth in connection with a particular machine, it should be understood that the invention is 105 not limited in the scope of its application to the particular machine which has been shown and described.

Having thus described my invention, I claim as new and desire to secure by Letters Patent of the United States:

1. A machine of the class described, having, in combination, a shaft, a cutting tool mounted upon the end thereof, a stationary suction conduit the mouth of which extends around said tool and serves as a gage to limit the depth of cut of said tool, and means for rotating said shaft.
2. A machine of the class described, having, in combination, a shaft, a cutting tool mounted upon the end thereof, a suction conduit the mouth of which extends around said tool and serves as a gage to limit the depth of cut of said tool; means for rotating said shaft, and means whereby relative adjustment between said tool and the mouth of said conduit may be produced to increase or decrease the depth of cut.
- 3: A machine of the class described, having, in combination, an upright shaft, a cutting tool mounted on the end thereof, a stationary suction conduit through which said shaft passes; the mouth of said conduit extending around said tool and serving as a gage to determine the depth of cut of said tool, and means for rotating said shaft.
4. A machine of the class described, having, in combination, an upright shaft, a cutting tool mounted on the end thereof, a suc-

tion conduit through which said shaft passes, the mouth of said conduit extending around said tool and serving as a gage to determine the depth of cut of said tool, means 35 for rotating said shaft, and means for producing relative adjustment between said shaft and the mouth of said conduit.

5. An insole heel seat smoothing machine, having in combination, a rotary shaft, 40 an end milling cutter mounted on the end thereof, the construction being such that the

45

shaft may be caused to project into a shoe to bring the heel portion of the insole there-

45

of into contact with the cutter, and a suc-

45

tion conduit having its mouth encircling the cutter and shaped to permit the cutter to

45

operate close to the heel end of the insole.

6. An insole heel seat smoothing machine, having in combination, a rotary shaft, 50 an end milling cutter mounted on the end

50

thereof and shaped to smooth the heel por-

50

tion of the insole of a shoe, a suction conduit adapted to protect the lining of the shoe from the action of the cutter, and means 55 whereby relative adjustment between the cutter and the mouth of the conduit may be produced to vary the depth of cut made in the insole.

In testimony whereof I have signed my 60 name to this specification.

BERNARD THOMAS LEVEQUE.
